UNITED STATES PATENT OFFICE.

JOHN MAXWELL, OF ONEIDA, NEW YORK.

DESIGN FOR A BURIAL-CASKET LID.

SPECIFICATION forming part of Design No. 17,650, dated August 23, 1887.

Application filed May 7, 1887. Serial No. 237,485. Term of patent 7 years.

To all whom it may concern:

Be it known that I, JOHN MAXWELL, of Oneida, in the county of Madison, in the State of New York, have invented a new and useful 5 Design for Metallic Burial-Casket Lids, of which the following, taken in connection with the accompanying drawings, is a full, clear, and exact description.

This design pertains chiefly to the foot-section of metallic burial-casket lids.

In the annexed drawings Figure 1 represents a plan view of a casket-lid embodying my design, and Fig. 2 is a transverse section on line $x x$, Fig. 1.

15 The leading feature of my design consists in a raised or struck-up central portion of the foot-section of the lid to a plane above the marginal portion thereof, and a tapered raised central portion toward the foot of the lid, the said 20 portion being in the form of an acute angle, the upper part of the raised central portion being embellished by figures extending from the base of the triangle toward the apex thereof.

The letter A indicates the top of the angular foot portion of the lid, which has its base 25 adjoining the plain portion B of said lid. The angular portion from the base extends toward

the foot of the lid, terminating in an apex, c. The top of the angular portion is embellished or ornamented by a figure, c, extending from 30 the points d at each side toward the apex e and terminating at a central point, g, thus following the general contour of the angular top panel of the foot portion of the lid.

What I desire to claim is—

35 The design for the lids of burial-caskets herein shown and described, the same consisting of the raised foot portion extending from the plain head-section at an acute angle toward the foot of the lid, the top panel of the 40 said foot-section being embellished by an ornamental figure extending from the points d to the central point, g, and following the general contour of the angular top panel of the lid.

In testimony whereof I have hereunto signed 45 my name and affixed my seal, in the presence of two attesting witnesses, at Oneida, in the county of Madison, in the State of New York, this 3d day of May, 1887.

JOHN MAXWELL. [I. S.]
